[57] CLAIM

The ornamental design for a dieter's dish, substantially as shown and described.

DESCRIPTION

FIG. 1 is a top front perspective view of a dieter's dish showing our new design;

FIG. 2 is a top plan view thereof;

FIG. 3 is a front elevational view thereof;

FIG. 4 is a rear elevational view thereof; and

FIG. 5 is a right side elevational view thereof, the left side is a mirror image thereof.

The base of the dieter's dish is flat.
